Primary Examiner — Austin Murphy(74) *Attorney, Agent, or Firm* — Paul W. Martin(57) **CLAIM**

The ornamental design for a terminal, as shown and described.

DESCRIPTION

FIG. 1 is a front view;

FIG. 2 is a right view;

FIG. 3 is a left view;

FIG. 4 is a top view; and,

FIG. 5 is a perspective view.

The broken lines shown in the drawings represent portions of the terminal that form no part of the claimed design.
